UNITED STATES PATENT OFFICE

2,612,360

BUBBLE CAP AND HOLDDOWN DEVICE

Charles L. Haynes, Flintridge, and Henry W. Breer, Burbank, Calif., assignors to C. F. Braun & Co., Alhambra, Calif., a corporation of California

Application February 1, 1947, Serial No. 725,821

2 Claims. (Cl. 261—114)

1

This invention relates to bubble columns of the type employed in the processing of hydrocarbons and is particularly directed to an improved bubble cap and holdown means therefor for use on a bubble column tray.

The principal objects of this invention are to provide a bubble cap and riser assembly which may be assembled and removed from the top of the tray, using only the simplest of tools.

Another object is to provide such a cap and riser assembly which may be removed after a period of service without requiring that any parts thereof be unthreaded.

Another object is to provide a bubble tray device which may be fully assembled before shipment for installation on a bubble column, the various elements of the device being securely fastened together to avoid separation and loss occasioned by vibration during shipment.

More detailed objects include providing a cap and riser assembly in which the cap has an inclined surface for cooperation with a wedge insertable between the cap and an abutment on a holdown element which extends through the cap.

It is another object to provide an arrangement of this type in which the holdown element is secured against upward movement by an anchor member which extends under the tray in a position below several cap and riser assemblies.

Another object is to provide a holdown device for a cap and riser assembly which includes a novel type of tapered wedge having a longitudinal slot extending from its small end.

Various other objects and advantageous features of this invention may be had from the following description, and one embodiment thereof may be seen in the accompanying drawings wherein similar characters of reference designate corresponding parts, and wherein:

Figure 1 is a diagrammatic sectional elevation of a portion of a bubble tower showing cap and riser assemblies mounted on bubble trays in the tower and cap and riser assemblies on the trays comprising a preferred embodiment of this invention;

Figure 2 is a sectional plan view of the device shown in Figure 1;

Figure 3 shows a sectional elevation of a cap and riser assembly of a preferred type, and illustrated on an enlarged scale;

Figure 4 is a sectional elevation taken substantially on the lines 4—4 as shown in Figure 3;

Figure 5 is a perspective view showing a preferred form of tapered wedge adapted for use in connection with this invention;

2

Figure 6 is a perspective view showing a modified type of wedge;

Figure 7 is a perspective view showing a further modified form of wedge;

Figure 8 is a sectional elevation partly broken away showing a modified form of holdown device;

Figure 9 is a sectional elevation partly broken away illustrating a modified form of riser employed in connection with this invention.

Referring to the drawings, a bubble column 10 is provided with the usual horizontal bubble trays 11, 12 and 13 and secured on these trays are cap and riser assemblies generally designated 14. Down pipes 15 having weirs 16 at their upper ends serve to convey fluid downwardly from each tray to the tray therebeneath.

A shelf 17 secured in the bubble tower 10 by any convenient means, such as welding 18, ex-

tends around the inner periphery of the tower 10 and along the side of the down pipe 15. One of these shelves 17 is provided for each of the bubble trays 11, 12 and 13. The peripheral edge of each tray extends over the shelf to support

the tray against gravity. A plurality of openings 19 are provided through each tray and the cap and riser assemblies are positioned over these openings. Since the cap and riser assemblies on each of the trays are substantially duplicates, only one such assembly on the tray 11 will be described in detail.

Extending into an opening 19 in the tray 11 is the lower end of a riser 20. The ring 21 secured on the riser by any convenient means, such

as welding or brazing, rests on the upper surface of the tray 11 to prevent the riser 20 from dropping through the opening 19. The riser 20 may be of any convenient or desirable shape and, as shown in the drawings, comprises a generally

40 cylindrical element extending upwardly from the substantially horizontal surface 22 of the tray 11.

A bubble cap 23 in the form of an inverted cup is positioned concentrically with respect to the riser 20 and is carried thereby by a plurality of

45 supporting clips 24 fixed with the cap 23. The clips contact the upper edge 25 of the riser 20 to hold the cap in concentric relation as well as to maintain it at the proper elevation. A series of

50 tapering notches 26 are provided around the periphery of the bubble cap 23 adjacent its lower surface.

Means are provided for preventing upward movement of the cap and riser assembly relative to the tray 11 and, as shown on the drawing, this means includes a central hook-bolt 27 extending

upwardly through an opening 28 in the upper surface of the cap 23. The lower end of this hook-bolt 27 extends around and under a stationary anchor rod 29 to prevent upward movement of the element 27. The anchor member 29 extends under the tray 11 and under a plurality of the cap and riser assemblies 14 so that a single anchor member is used for securing a plurality of cap and riser assemblies relative to the tray 11. The anchor member 29 may be secured under the tray 11 by any convenient means, such as by welding 30.

The upper end of the hook-bolt 27 is slotted, as shown at 31, and the bottom of the slot is positioned below the upper surface of the cap 23, as shown in Figure 4. A nut 32 threaded on the upper end of the hook-bolt 27 presents an abutment or downwardly facing shoulder 33.

A portion of the upper surface of the bubble cap 23 is inclined, as shown at 34. A wedge member 35 having a substantially horizontal upper surface 36 and an inclined lower surface 37 is adapted to be inserted through the slot an aperture 31 between the shoulder 33 and the inclined surface 34. The angle of the lower surface 37 on the wedge is supplementary to the angle of inclination of the surface 34 so that the surfaces 34 and 37 and the surfaces 36 and 33 each contact over a substantial area.

A longitudinal slot 38 extends from the small end 39 of the wedge member 35 to a position between the abutment 33 and the inclined surface 34 so that upon driving the wedge transversely of the hook-bolt 27 toward locking position or upon threading the nut 32 downward on the hook-bolt 27, additional resilience over the inherent resilient material of the wedge 35 is obtained between the abutment 33 and the inclined surface 34. This resilience or springiness acts in the nature of a lock washer to prevent disassembly of the parts upon vibration, such as may occur during shipment. Furthermore, the wedge 35 may be retained against disassembly by deflecting one of the upper or lower fingers 40 and 41 which are separated by the slot 38. The wedge 35 is preferably constructed of steel or alloy steel which will permit deformation of the fingers 40 and 41 without fracture.

In the operation of the device, fluid admitted into the upper portion of the bubble tower travels downwardly through the down pipes 15 and across the trays 11, 12 and 13, while vapor admitted into the lower end of the bubble column passes upwardly through the openings 19 in the bubble trays and intimately commingles with the fluid on the trays as it passes over the upper edge of the riser and escapes outwardly through the slots 26 provided in the bubble caps 23.

After a period of use the parts may become corroded or coke-like deposits may build up. When the extent of corrosion or build up of deposits reduces the efficiency of the bubble tower below an acceptable limit, the operation of the tower is suspended for cleaning and repairs. Corrosion and deposits on the exposed surfaces make it undesirable or impossible to effect any unthreading of the parts for the purpose of disassembly. The nut 32 may be left in its initial position and the upper finger 40 on the wedge 35 may be deflected back to approximate parallelism with the lower finger 41 by means of a hammer or other simple tool. The wedge may be withdrawn from the slot by means of a hammer blow on the small end 39 of the wedge. With the wedge 35 removed, the hook-bolt 27 may be

lowered sufficiently to release the engagement between the lower end of the hook-bolt and the anchor rod 29. The entire cap and riser assembly then may be withdrawn upwardly from the bubble tray.

After cleaning or replacement of defective or corroded parts, the cap and riser assembly may be reinstalled on the bubble tray by first engaging the lower end of the hook-bolt 27 under the anchor rod 29 and then driving a wedge 35 into the slot 31 in the bolt.

It should be noted that the operation of removing and replacing the cap and riser assembly may be accomplished entirely from the upper side of the particular bubble tray 11 involved and that it is unnecessary to insert or fasten a portion of the assembly from the underside of the tray. A single workman on the underside of the tray can therefore remove and replace the cap and riser assemblies 14 without assistance from below.

The modified form of wedge 42 shown in Figure 6 is formed from a single length of material folded or doubled at 43 to provide a long leg 44 and a short leg 44a. These legs lie back to back with substantially no space between them, and may both be inserted as a unit into the slot 31 in the holdown bolt 27. The upper surfaces 45 may be substantially horizontal and the surfaces 46 inclined at an angle supplementary to the angle of inclination of the surface 34. The legs 44 and 44a may be spread to prevent displacement after the wedge 42 is in place in the slot 31.

The U-shaped wedge 55 shown in Figure 7 is similar to the wedge 42 except that the legs 56 and 56a are spaced by the end member 57. The upper surfaces 58 are horizontal to cooperate with the shoulder 33 and the lower inclined surfaces 59 are adapted to rest on the inclined surface 34. This modified form of wedge does not require that the hook-bolt 27 be slotted since the wedge passes under the nut 32 and receives the shank of the hook-bolt between the parallel sides 43.

In Figure 9 a modified form of support for the riser is shown. In this modification, the riser 20c is radially expanded along a circumferential line near its lower end to provide a lateral extension 21c which will support the riser 20c on the bubble tray 11 and prevent the riser 20c from dropping through the opening 19. This integral lateral extension 21c may be employed instead of the ring 21, if desired.

Having fully described our invention, it is to be understood that we do not wish to be limited to the details herein set forth, but our invention is of the full scope of the appended claims.

We claim:

1. In a cap and riser assembly for a bubble tray, the combination of: a cap, a holdown element extending upward through an opening in the cap, a downwardly facing shoulder on the holdown element, an upwardly facing inclined surface on said cap, a tapered wedge member insertable between said shoulder and the inclined surface of the cap, the wedge member having surface contact with the shoulder, the wedge member having a longitudinal slot extending from its small end and underlying the entire extent of said shoulder, the slot extending lengthwise beyond the shoulder in both directions to give the wedge member resiliency and thereby to provide a resilient connection.

2. In a cap and riser assembly for a bubble tray, the combination of: a cap, a holdown bolt

projecting upwardly through an opening in the cap, means to secure the lower end of the hold-down bolt, a central transverse aperture extending axially of the bolt from the projecting end thereof, a nut threaded on the projecting end of the holddown bolt, an upwardly facing inclined surface on the cap, a tapered wedge insertable through the aperture between the nut and the inclined surface of the cap, the wedge having surface contact with the nut, and a transverse slot in the wedge extending under the full extent of the nut from the small end of the wedge, the slot extending lengthwise beyond the shoulder in both directions to give the wedge resiliency and thereby to provide a resilient connection.
